UNITED STATES PATENT OFFICE.

HUBERT FLOEHR, OF DEFIANCE, OHIO.

FIRE-ESCAPE APPARATUS.

1,258,759.

Specification of Letters Patent. Patented Mar. 12, 1918.

Application filed May 11, 1916. Serial No. 96,840.

To all whom it may concern:

Be it known that I, HUBERT FLOEHR, a citizen of the United States, residing at Defiance, in the county of Defiance, State of Ohio, have invented certain new and useful Improvements in Fire-Escape Apparatus; and I do hereby declare the following to be a full, clear, and exact description of the invention, such as will enable others skilled in the art to which it appertains to make and use the same.

This invention relates to safety appliances and is directed more particularly to fire escape apparatus of improved and novel construction.

An object of the present invention resides in the provision of a fire escape apparatus which may be quickly and easily assembled for use and as readily disassembled, one which will embody the desired features of simplicity, efficiency, reliability and convenience, and which in addition may be manufactured and marketed at a relatively low cost.

A further object of the invention is to provide a transportable fire escape including an escape chute normally wound upon a drum and adapted to be unwound therefrom and set up in novel manner whereby to provide a tubular chute having entrance and exit openings.

With the above and other objects of similar nature in view, the invention consists in the construction, combination and arrangement of parts, set forth in and falling within the scope of the appended claim.

In the drawing:

Figure 1 is a side elevation of the invention in position for use,

Fig. 2 is a top plan view thereof,

Fig. 3 is a detail section taken transversely through the winding drum with the escape chute in position to be transported, and,

Fig. 4 is a detail perspective of the drum, and a portion of the escape chute, illustrating the manner of adapting the latter for use.

Referring now more particularly to the accompanying drawing, there is shown the rear portion of a motor vehicle A, including a specially constructed body 10 open at the top and provided with a platform 11, said platform and the side walls of the body 10 being suitably cushioned as indicated at 12

to prevent injuring the persons employing the escape.

Journalized transversely of the body 10 is a shaft 13 on which is mounted a winding drum 14, said shaft having one end extended outwardly of the body and squared as indicated at 15 for the reception of a crank 16 by which the drum 14 may be rotated. Secured at one end to the drum 14 is a length or strip of flexible material 17, and this strip when in normal position is wound flat upon the drum as clearly shown in Figs. 3 and 4 in which manner it may be conveniently transported from place to place as occasion demands. Provided on the longitudinal margins of the strip 17 are fastening devices 18 which may be of any desired construction and are arranged transversely in pairs for coöperation when disposing the escape in position for use. At the outer end of the strip 17 a ring 19 is suitably secured and provides an entrance opening 20 for the escape as will be subsequently apparent.

This ring 19 has further secured thereto a hook 21 for engagement with a window sill or other suitable support, to properly suspend the escape chute in its operative position.

To adapt the device for use the strip 17 is unwound from the drum and elevated to the desired position by means of a rope, (not shown) suitably attached to the ring 19 and thrown to an occupant of the building in which the fire is in progress. As the strip is unwound from the drum its longitudinal margins are brought together or folded in overlapped relation whereby successive pairs of fasteners may be quickly connected or assembled. Thus as the strip is elevated to the desired position on the building, the same is progressively converted into a tubular escape chute as indicated in Figs. 1 and 2 in which the ring 19 provides the entrance opening while the exit thereof is adjacent the drum and is outlined thereby and by the divergent margins of the strip below the last assembled fasteners.

In employing the device, the chute is assembled and positioned as indicated in Fig. 1 so that a person may readily enter the tube through the ring 19 and be safely conveyed to the platform 11, the cushions 12 obviating possibility of injury as is evident.

What I claim is:

A fire escape comprising in combination

with a support, a drum rotatably mounted in the support, a strip of flexible material secured at one end to and wound flat upon the drum and provided with fastening devices along its longitudinal margins, and a ring secured to the free end of the fabric having means for attaching it to a support, said flexible strip being adapted to be unwound from the drum and foldable to over-
lap said margins and connect said fastening

devices whereby to provide a continuous tubular chute of which said ring constitutes the entrance opening while its point of exit is across the periphery of the drum.

In testimony whereof, I affix my signature, in the presence of two witnesses.

HUBERT FLOEHR.
